UNITED STATES PATENT OFFICE

HENRY MOELLER, OF COLUMBUS, OHIO

DESIGN FOR A WATCH DIAL OR SIMILAR ARTICLE

Application filed February 27, 1930. Serial No. 34,670. Term of patent 7 years.

To all whom it may concern:

Be it known that I, HENRY MOELLER, a citizen of the United States, residing at Columbus, in the county of Franklin and State of Ohio, have invented a new, original, and ornamental Design for a Watch Dial or Similar Article, of which the following is a specification, reference being had to the accompanying drawing, forming part thereof.

The figure is a plan view of a watch dial or similar article, showing my new design.

I claim:

The ornamental design for a watch dial or similar article as shown.

HENRY MOELLER.
